Primary Examiner — Janice Hallmark(74) *Attorney, Agent, or Firm* — Rumit Ranjit Kanakia(57) **CLAIM**

The ornamental design for a waterproof phone holder, as shown and described.

DESCRIPTION

FIG. 1 is a front elevational view of a waterproof phone holder showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another front elevational view of the waterproof phone holder of FIG. 1 shown in an alternate position with the bracket portion open;

FIG. 9 is another perspective view thereof, showing the waterproof phone holder in an alternate position with the bracket portion open;

FIG. 10 is another front elevational view thereof, showing the waterproof phone holder in an alternate position with the front cover and bracket portions open; and,

FIG. 11 is another perspective view thereof, showing the waterproof phone holder in an alternate position with the front cover and bracket portions open.
